UNITED STATES PATENT OFFICE.

ALEXANDER S. SPIEGEL AND LOWELL F. LINDLEY, OF CHICAGO, ILLINOIS.

ROOFING MATERIAL.

1,157,438.

Specification of Letters Patent. Patented Oct. 19, 1915.

Application filed January 28, 1914. Serial No. 815,058.

To all whom it may concern:

Be it known that we, ALEXANDER S. SPIEGEL and LOWELL F. LINDLEY, citizens of the United States, residing at Chicago, Illinois, 5 have invented certain new and useful Improvements in Roofing Material, of which the following is a specification.

This invention relates to prepared roofing and particularly shingles made therefrom. As at present made shingles of this 10 character are cut from the prepared material which is built up of several layers consisting of a base of felt covered with a composition coating upon which, while plastic, is sprinkled sand or grit. When the 15 shingle is laid only about four inches of it is exposed to the weather as the remainder thereof is covered by the next row, etc.

Now the particular object of this invention is to provide a way of covering the felt base of the shingle with a coating and sand only where it will be exposed to the weather.

With this and other objects in view the invention consists in the construction and 25 arrangement of parts hereinafter described and more particularly pointed out in the claims, it being understood that we do not wish to limit ourselves to the details of our invention.

We have illustrated our invention in the 30 accompanying drawings in which—

Figure 1 shows a side elevation of the machine for coating the roofing in the present manner. Fig. 1^a shows a modification of 35 the coating thickness regulator. Fig. 2 shows a sectional view with one of our guides in place. Fig. 3 shows a sectional plan view of the coating machine with four 40 guides in place. Fig. 4 shows the material coated according to this invention and from which shingles may be cut. Fig. 5 shows a special form of roofing coated according to this invention. Fig. 6 shows a section of a shingle made according to this invention.

In the drawings, the ordinal 6 indicates a 45 reservoir containing the coating material arranged to feed this material 7 onto the felt base 8 of the shingles as it passes over a table 9 from a roll 10. This roller 10 is provided under the felt and adjacent to the 50 table 9 to cause the felt to move along. A knife 11 is provided over the roll 10 and near the point where the coating 7 is fed to the felt for the purpose of spreading uni-

formly the coating upon the felt. This 55 knife 11 is adjustable as to its angle of slant upon its pivot 12 to vary the thickness of the coating compound upon the felt. We may modify this however, and use a roller 12' to regulate the thickness of the coating 60 as shown in Fig. 1^a. A hopper 13 is provided to feed sand or grit while the coating composition is still wet to which it sticks.

Now in order to limit the coating composition to only that portion of the felt base 65 that it is desired to cover, adjustable guides 14 are provided in front of the knife 11 and so arranged over the felt base that they will prevent the plastic coating composition from covering any other portion of the felt 70 except that between the guides as shown in Fig. 3. The sand or grit may be fed to the entire felt base as it will only stick to that portion whereon is the adhesive coating. The finished product of the arrangement 75 shown in Fig. 3, appears as Fig. 4 which consists of alternate strip of uncovered felt and felt covered with the coating and sand. This is then cut in two to form two strips 80 of material from which shingles of the new construction are cut.

The special roofing shown in Fig. 5 is made up of material as above described but is wider than the ordinary shingle material and in this case it is only desirable to have 85 a space of two inches at one side remain uncoated. This is accomplished in our device by only using one of the guides 14 to confine the coating material to within the two 90 inches of one edge it is desired to leave uncovered. However, we do not wish to confine ourselves to the products as shown in Figs. 4 and 5, as we may produce any article 95 consistent with the spirit of this invention, such for instance, as a shingle shown in Fig. 6.

We claim as our invention:—

1. As a new article of manufacture a composition roofing material adapted to be cut into shingles, comprising a single ply 100 fabric having applied thereon a plurality of protecting layers of adhesive and sand in continuous strips with alternate parallel strips of the exposed felt surface lying between said coated portions, and of substantially the same width so that when cut along the line of two adjoining strips to form 105 shingle stock having one end formed of sin-

gle layer and the other end, which is to be exposed to the weather, formed with a plurality of protecting layers.

2. As a new article of manufacture, composition roofing material adapted to be used as roofing or shingle stock comprising a single ply fabric having a plurality of continuous strips of layers of adhesive and sand applied to its surface, adapted to be exposed to the weather, the remaining portion forming an underlap being formed of the

single ply and being uncoated, said coated and uncoated strips being of substantially equal areas, substantially as described.

In testimony whereof, we affix our signatures in presence of two witnesses. 15

ALEXANDER S. SPIEGEL.
LOWELL F. LINDLEY.
